[57] CLAIM

The ornamental design for a sprinkler head, substantially as shown and described.

DESCRIPTION

FIG. 1 is a perspective view of a sprinkler nozzle embodying the new design;

FIG. 2 is a top plan view thereof;

FIG. 3 is a bottom plan view thereof; and
FIG. 4 is a side elevational view thereof, the other sides being the same side as the side shown.

The fragmentary broken-line showing of a water supply riser pipe in FIG. 1 is for purposes of illustration only and forms no part of the claimed design.
